Primary Examiner — Cynthia Ramirez*Assistant Examiner* — Michael Maharajh(74) *Attorney, Agent, or Firm* — Timothy J. Monahan; Monahan & Company, LLC(57) **CLAIM**

The ornamental design for a dodecahedron die, as shown and described.

DESCRIPTION

FIG. 1 is a top view of the dodecahedron die with 1 pip, showing our new design.

FIG. 2 is a side view of the die showing the faces with 6, 5, 4, 8 and 9 pips.

FIG. 3 is a side view of the die showing the faces with 4, 3, 12 and 8 pips.

FIG. 4 is a side view of the die showing the faces with 3, 2, 10, 11 and 12 pips.

FIG. 5 is a side view of the die showing the faces with 2, 6, 9 and 10 pips; and,

FIG. 6 is a bottom view of the die seen perpendicular to the face with 7 pips.
